FRANCE.

HERMETIC GLASS COVERING.

Specification of Letters Patent. Patented Aug. 31, 1920.

1,351,492.

Application filed February 6, 1918. Serial No. 215,712.

To all whom it may concern:

Be it known that I, JEAN CHARLES SÉAILLES, of 1 Rue Médicis, at Paris, Department of the Seine, in France, citizen of the French Republic, have invented certain new and useful Improvements in Hermetic Glass Coverings; and I do hereby declare the following to be a full, clear, and exact description of the invention, such as will enable others skilled in the art to which it appertains to make and use the same.

This invention relates to glass tiles for covering buildings.

The object of the invention resides in the provision of plane tiles which are formed with one or more projections on one face thereof, which projections are adapted to be hooked together, so that a weather-tight joint will be produced.

In the drawing:

Figure 1 is a fragmental edge elevation showing the manner of assembling two of the tiles;

Fig. 2 is a similar view showing a different manner of assembling, wherein the innermost rib on one of the tiles is engaged between the ribs on the other;

Fig. 3 is a side elevation of a tile showing one manner of attaching it to the supporting rafters;

Fig. 4 is a similar view showing the tile held in place without supporting rafters;

Fig. 5 shows a modification of the manner of assembling the tiles;

Fig. 6 is a fragmental detail showing a modification of the manner of assembling the tiles, and

Fig. 7 is a diagrammatic view illustrating tiles which carry ribs on both faces.

The tiles illustrated in Figs. 1 and 2 are formed of glass with one plane face. The other face of the tile is provided adjacent to its opposite edges with ribs 1'. In Fig. 1 of the drawing the outermost rib of the tile 1 is illustrated as disposed between the ribs of the tile 2 and the joint between these tiles is supported by a rafter 4. The space between the ribs 1' of the tile 2 is filled with a varnish or cement (which may be of non-drying mineral oil), or with any other suitable material so as to produce a water-tight joint. The embedding of the rib 1' of the tile 1 in the cement 3 produces a joint from which the dust is excluded, so that the in-

filtration of the water by capillary attraction will be prevented.

It will be noted that the distance between the ribs and the tiles is greater than the width of the ribs themselves, so that the assembly of the tiles is greatly facilitated. In 60 the manufacture of the tiles there are naturally certain inconsistencies in the width of the ribs and the tiles, but the making of the spaces between the ribs of greater width than the ribs themselves allows for these 65 inconsistencies, so that there will be no difficulty in engaging the ribs of one tile between the ribs of the other and adjacent tile.

In Fig. 2 the tile 1 is disclosed in such position that the innermost rib engages between the ribs of the tile 2. In this form, as in Fig. 1, the space between the ribs 1' of the tile 2 is filled with cement or the like, and the joint between the tiles is supported on the rafter 4.

In Fig. 3 one method of attaching the tiles is disclosed. At the upper end of the supporting rafter 4 a simple cleat or catch 5 is provided, which is preferably made of metal, and which overlaps the upper edge of 80 the tile to maintain the same in contact with the rafter 4. At the lower end of the rafter a buffer or stop 6 is located. This buffer prevents the sliding of the tile and also the lifting of the same.

In Fig. 4 a somewhat similar arrangement is disclosed wherein the rafter 4 is dispensed with and the tile is merely supported at its ends on the beams 4', being held in place at its lower end by the buffer or stop 6, and at 90 its upper end by an angle cleat 5'.

Fig. 5 discloses diagrammatically a modified method of assembling, wherein the tiles are each provided with one projecting rib 1' at each edge. These ribs are alternately arranged in overlapping relation and the joints between the ribs are supported on the rafters 4. It will be noted that the ribs of the tiles 1 extend downwardly, while the ribs of the tiles 2 extend upwardly. These 100 tiles are held in place by suitable cleats 6'.

In Fig. 6 of the drawing the tiles 1 and 2 are shown as being provided with two parallel ribs 1' which are interengaged and the joint between the tiles is supported on 105 the rafter 4. The stops 7, 8 and 9 are provided to prevent any displacement of the tiles.

Fig. 7 illustrates the tiles 1 and 2 as being provided at one edge with upwardly extending ribs 1' and at the other edge with downwardly extending ribs 1'. In this form the 5 downwardly extending ribs of the tile 1 engage with the upwardly extending ribs of the tile 2, and the joints between the tiles are supported on the rafters 4.

The provision of the ribs adjacent to the 10 edges of the tiles insures the accumulation of the water at the edges, and also insures the conducting of the water from the tiles before it enters through the joints between the tiles.

15 What I claim is:—

A construction of the glass described, consisting of a pair of glass tiles having their

ends overlapping, each of said tiles having at least two spaced ribs, the transverse spaces between the ribs being greater than 20 the width of the ribs themselves and a filler of adhesive material disposed between at least one pair of said ribs and in which one of the ribs of the opposed tile is embedded, the faces of the tile being flat and smooth 25 offering an unobstructed water shed for the lapped and overlapping tiles and a flat supporting underface for the overlapped tile.

In testimony whereof I affix my signature, in presence of two witnesses.

JEAN CHARLES SÉAILLES.

Witnesses:

EMILE BERTRONOF,
CHAS. P. PRESSLY.
